DES. 2435

George Klimrod and Charles G. Moulton of Chicago Ill.

Assignors to

George Klimrod.

Letters Patent No. 2435. Dated Sept. 25. 1866.

Design for Store Plates.

The Schedule referred to in these Letters Patent and making part of the same,

To all whom it may concern:

Be it known that we, George Klimrod and Charles G. Moulton of the City of Chicago, in the County of Cook and State of Illinois, have originated and designed a new and useful Pattern to be cast upon Stores, of which the following is a full, clear and exact description, reference being had to the accompanying drawing making part of this Specification.

The pattern which we claim is shown at letter "A" in the drawing, and is an Oval Medallion within which is a figure having eight star like points, each point touching, or nearly touching the rim of the Medallion, with an ornament in the centre of the figure as shown, and with ornamentation within each star like point, and between all the star like points as shown, which pattern is to be cast in Alto relief on the doors of the stores or on a part of the door only as may be desired.

What we claim as our invention and desire to secure by Letters Patent is;

The Design or pattern to be cast upon stores as herein shown.

Witnesses.

John R. Porous.

Henry King.
